UNITED STATES PATENT OFFICE

SIDNEY G. BROWN, OF SARATOGA SPRINGS, NEW YORK.

EXPRESS RECEIPT AND SHIPPING-TAG.

1,175,594.

Specification of Letters Patent. Patented Mar. 14, 1916.

Application filed August 11, 1914. Serial No. 856,159.

To all whom it may concern:

Be it known that I, SIDNEY G. BROWN, a citizen of the United States, residing at Saratoga Springs, in the county of Saratoga 5 and State of New York, have invented certain new and useful Improvements in Express Receipts and Shipping-Tags, of which the following is a specification.

My invention relates to improvement in 10 express receipts and shipping tags and the object of my invention is to provide a combination express receipt and way-bill together with such elements and combinations as are hereinafter more particularly set 15 forth and claimed. I accomplish these objects as illustrated on the accompanying drawings in which,

Figure 1, is a perspective of my combination receipt and way-bill. Fig. 2, a plan 20 of one of the leaves of my combined express receipt and way-bill. Fig. 3 is a view of the way-bill attached to a package after the detachable leaves are removed therefrom. Fig. 4 is a view of the way-bill when ar- 25 ranged for attachment to a package by means of wires. Fig. 5 is a view of the way-bill attached to a package with some of the detachable leaves in connection therewith. Fig. 6 is a view of a modified form of at- 30 taching my way-bill to a package.

Similar letters refer to similar parts throughout the several views.

I construct a folder A of good Manila paper, preferably, or it may be of tag linen 35 if desired, and print on the faces, 1, and 5 thereof certain directions and descriptions as may be necessary in order to show, to those who transport or carry the article to which it is attached, from whom it is re- 40 ceived; to whom it is going; the various routes, etc. To one of the leaves of the folder, 1, I form a flap B, which may be done by turning over the leaf of the folder as shown in Fig. 1. Between the leaves 1 45 and 5 of the folder I place a series of detachable leaves 2, 3 and 4 which are preferably made of comparatively thin paper and carbon sheets are placed between the leaves so that all of the leaves are filled in by 50 writing on leaf 1. The detachable leaves, 2, 3, and 4, are secured to leaf 5, by suitable wire clips, C, although I do not limit myself to this mode of attachment. I preferably place an eyelet D through the folder and 55 the detachable leaves as shown on the figures. The flap B is gummed on the side, b',

thereof or on both sides so that it may be moistened and pasted to the article to be shipped. When an article is such that it is not desirable or it is not possible to thus 60 secure the receipt to it I use a flexible wire, 10, which passes through eyelet D and is attached to the article to be shipped. (See Fig. 4.)

On each of the leaves of my com- 65 bined receipt and way-bill I form a series of spaces between parallel lines drawn transversely across the leaf. Beginning at the top of the leaf I form a space E, between the lines e and f and within this space E, I 70 print the name of the company issuing the receipt together with the word From, leaving a space within which may be written the name of the office issuing it. In the next space F between the parallel lines f and g I 75 place the words To— State—, leaving a blank space for the insertion of the name of the place to which the article is to be sent. In the next space G, I print Date with a space for the insertion of the time of the 80 receipt of the goods. I also preferably insert between the parallel lines g and h, a portion of which is used for receiving the date, the word Number and a space for inserting the number of the bill. In the drawings this 85 number is shown as A—53180. In the next space H, I place the word Consignee with a space for the insertion of the consignee's name. In the next space J, I place the destination or local address leaving room to 90 insert that information. In the next space K, I print Shipper and leave a space for writing the shipper's name. In the next space L, I print Routings via, and leave room for inserting that information. In 95 the next space M, I print the word, Weight, beneath it leaving room for inserting the weight. I also print the word Rate with room for inserting it. I also print the words Express chg. prepaid, also the word 100 Value and leave room for placing the amount of value within. In the next space N, between the parallel lines m and n, I print Lot shipment on—, leaving room to insert a number and then follow with the 105 printed word Pieces. I also print within the space N the words Bill No. with a blank space followed by the words For charges. At the bottom of the leaf I have an enlarged space O, containing the printed word Arti- 110 cles, leaving room to inventory the articles to which the express receipt refers. At the

bottom of the leaf I print the word Pre-paid. Each of the leaves making up and forming this combination receipt and way-bill have the same printed matter on them 5 and when they are put in proper position in the folder each of the spaces registers with like spaces on the leaves forming the folder. Thus when carbons are placed between the leaves writing on the first leaf fills in the 10 corresponding spaces in each. I do not however limit myself to the particular words printed on the leaves, nor the exact location of the various information given thereby. These words may be changed and their location 15 on the leaf altered without materially changing the substance of my invention.

The back of leaf #1 is blank and may be used for messenger and junction records.

My receipt and way-bill combined is used 20 as follows: After the carbons have been inserted between the leaves and the spaces filled in by writing on the first sheet, which of course fills in the spaces on the others, the coupon #2, is detached, receipted on 25 the back and delivered to the consignor. Coupon #1 is then turned over bringing the face of the coupon next to the package. The flap, B, is turned so that the gummed portion, b, thereof which, when the coupon is 30 in the position shown in Fig. 1 is next adjoining the back of the coupon, is when in the position shown in Fig. 5 adjacent to and may be stuck on to the article upon which it is to be attached. The back side of coupon 35 #5 may be pasted to the package by applying mucilage thereto. When the driver reaches the office the charges and weight are inserted on coupons #1, 3, 4 and 5; coupon #3 is detached and retained for forwarding 40 office reference; coupon #4 is also detached and either sent to the receiving office or to the auditor daily. After this only coupons #1 and 5 are left on the package, as shown in Fig. 3. If the article is such that it can- 45 not be well secured by pasting, it may be fastened by the wire, 10, as shown in Fig. 4, after which the flap may be pasted to the back of coupon #5, thus, in each case, the face of coupon #5 and the back of coupon 50 #1 only is exposed when on the package. Coupon #5 gives the address of the shipment and coupon #1 provides spaces for

messenger and junction point records of handling. When the shipment reaches its 55 destination, coupon #1 may be easily detached by cutting it along the line of the flap and along the line of connection with coupon #5. Coupon #1 is then used by the receiving office to make receiving report and the coupon is sent to the auditor with the 60 report. The auditor then has full record of the handling of the shipment.

In Fig. 6 I show the way-bill attached to a package in which the flap, B, is gummed on the opposite side from that shown in the 65 other figures at b' and attached to the package as illustrated in Fig. 6.

Every package has a given bill number and in the illustration this is A 53180, making identification possible. When customers 70 present receipt for tracing, a number is on the receipt from which to trace and locate.

What I claim as my invention and desire to secure by United States patent is:—

A combined express receipt and way-bill, 75 comprising a folder made up of two leaves, front and back; a series of detachable sheets placed between said leaves; each of the leaves of the folder and the intervening sheets containing a printed receipt and way-bill form in blank, which forms are in registration when the leaves and sheets are superposed; a gummed flap formed on the front leaf of the folder; the back side of the other leaf of the folder adapted to be secured to a 80 package, exposing, after the detachable sheets are removed, the express receipt and way-bill on its front side; the gummed flap on the first leaf of the folder adapted to be pasted in such position as to cover the express receipt and way-bill on the front leaf; and the leaf of the folder which has the express receipt and way-bill concealed adapted to be detached when the package reaches 85 its destination, leaving the other leaf of the folder with the express receipt and way-bill exposed on the package attached to the 90 package.

In testimony whereof, I affix my signature in presence of two witnesses.

SIDNEY G. BROWN.
